UNITED STATES PATENT OFFICE.

JAMES WYNDHAM MEEK, OF LONDON, ENGLAND, ASSIGNOR OF ONE-HALF TO DAVID BROWN
THOMAS, OF LONDON, ENGLAND.

DAYLIGHT DEVELOPING APPARATUS.

No. 927,155.

Specification of Letters Patent.

Patented July 6, 1909.

Application filed February 16, 1909. Serial No. 478,146.

To all whom it may concern:

Be it known that I, JAMES WYNDHAM MEEK, a subject of the King of Great Britain and Ireland, and residing at 32 Albert road, Stroud Green, London, N., England, have invented certain new and useful Improvements in Daylight Developing Apparatus, of which the following is a specification.

10 This invention relates to apparatus for use in the development of photographic roll films in daylight and other actinic light, and particularly to apparatus having an opaque apron in which the film and its black paper can be wound up and then transferred to a developing tank without exposing the sensitized surface of the film to light. In apparatus of this type hitherto adopted it is necessary to use a separate cumbersome dark 15 box fitted with appliances for winding the film from its spool onto the apron, and then to remove the latter with the film from the separate dark box and transfer it to a developing tank.

20 The object of the present invention is to provide a very compact form of dark box or container for the apron and film and its black paper, which together with the contained apron and film can be bodily inserted 25 in the developing tank.

The invention consists in providing a container with a detachable spool box which is adapted to receive the exposed spool direct from the camera, and from which the film is wound into the container at same time as the apron, the spool box being then removed so as to enable the container, inclosing both the apron and film, to be placed in a developing tank.

30 40 The accompanying drawings illustrate one form of daylight developing apparatus according to the invention.

Figure 1 is a longitudinal section of the container with the spool box attached thereto, the section being taken on the line I—I Fig. 2. Fig. 2 is a transverse section on the line II—II Fig. 1. Figs. 3 and 4 are end views of the container with the spool box attached thereto. Fig. 5 is an outside 45 view of the closed container, with the spool box removed. Fig. 6 is a transverse section of the container fitted with the spool box and illustrating the manner in which the film and apron are wound. Fig. 7 is a detail 50

view of one end of the apron. Fig. 8 is a 55 sectional elevation of a developing tank.

In carrying out the invention according to one mode a container, 1, is provided with holes, 3, in its ends, 2, for the ingress and egress of liquid and air, the holes being 60 shielded by flanges, 4, on a reel spindle, 5, to prevent the inlet of light. The container, 1, has a large opening closed by a door, 7, hinged at 6 and secured in any suitable manner, as for instance by a wire, 28, sliding in loops 37, on the door, 7, and into a loop, 38, on the container, 1.

The door, 7, has an aperture, 8, alongside of which are ledges, 11, under which the flanges, 10, of a spool box, 9, are adapted to slide when the box, 9, is to be attached to the container, the end, 12, of the box, 9, abutting against a flange, 13, on the door, 7. The end, 12, may be provided with packing strips, 39, of velvet or the like, to exclude light. For a similar reason the door, 7, may be formed with a ridge, 14, either integral therewith, or soldered thereto, the ridge in the example shown being in the form of a wire. At the ends it forms in conjunction with the flanges, 13, a groove 15, into which the ends, 2, of the container enter when the door, 7, is closed.

The reel spindle, 5, is provided with milled heads, 18, 19, by either of which it can be readily rotated and a slight braking resistance is afforded by a spring, 17, Fig. 4, bearing on a portion, 16, of the head, 19, which portion is preferably of polygonal form. The spindle, 5, also has a wire loop, 26, for holding the end of the usual black paper strip 29, to which the film is attached, and further with hooks, 27, for receiving hooks, 25, on the end of an opaque celluloid or other suitable apron, 21, having side ridges, 22, for maintaining the sensitive surface of the film out of contact with the apron. The end of the apron is passed into the container, 1, through an aperture, 24, and a passage between the outer wall of the casing and an inner partition, 23.

The spool box, 9, is fitted with pivots, 31, 32, for the usual film spool, 30, the pivot, 32, having a head, 34, by which it can be withdrawn slightly against the action of a spring, 33, to enable the spool, 30, to be inserted or removed.

In use the end of the apron, 22, is first passed into the casing, 1, as before described

ready to be attached to the spindle, 5. The exposed film on its spool, 30, is then placed in the spool box, 9, and the latter is slid onto the door, 7, of the casing. The door, 7, is 5 opened, the usual paper seal of the exposed spool is broken and the end of the black paper strip, 29, is passed under and clipped by the wire, 26. The end of the apron is next attached to hooks, 27, and the door, 7, is 10 closed the parts assuming the positions indicated in Fig. 6 whereupon the spindle, 5, is rotated by one of the heads, 18 or 19, and the film and apron are wound onto the spindle. After they have been completely 15 wound thereon, the spool box, 9, is removed and the container, 1, with the film and apron therein is immersed in the developing tank, 35, which is filled with any suitable developing solution up to the level indicating beading, 36. The container, 1, is raised and lowered once or twice to expel the air and insure proper access of liquid to all parts of the film after which it is allowed to stand for a few minutes. It is then preferably 20 removed inverted and again inserted and allowed to remain for a sufficient time to complete the development after which it is removed placed in a washing bath or under a tap and then placed in a fixing bath. If 25 desired the film may be removed from the container before fixing to insure a thorough 30 washing.

It will be understood that when the film is not attached at the rear end to the black 35 paper strip, the loose end of the film should be attached to the black paper backing before the spool is placed in the spool box, and also, that when not so provided by the makers of the film it is desirable to mark the 40 paper near the end with the word "Stop" or "Halt" or with an equivalent mark or indication to warn the operator when the initial winding from the spool to the reel should cease to enable apron, 22, to be attached 45 when the door, 7, must be closed to protect the film from light until developed.

Having now described my invention what I claim as new and desire to secure by Letters Patent is:—

50 1. Apparatus for developing photographic roll films in daylight comprising a container having an opening in its side, a reel spindle within the container, an opaque apron adapted to pass through the aforesaid opening and to be wound on the reel spindle, and means for containing a film spool adapted to allow the film to be wound on the reel spindle simultaneously with the apron, substantially as and for the purpose hereinbefore set forth.

55 2. Apparatus for developing photographic roll films in daylight comprising a container having an opening in its side, a reel spindle within the container, an opaque apron adapted to pass through the aforesaid open-

ing and to be wound on the reel spindle, and a spool box, means for detachably securing said spool box to the container substantially as and for the purpose hereinbefore set forth.

3. Apparatus for developing photographic 70 roll films in daylight comprising a container having an opening in its side, a reel spindle within the container, an opaque apron adapted to pass through the aforesaid opening and to be wound on the reel spindle a hinged door on the container and having an opening a spool box, and means for securing said spool box to the door coincidently with the opening therein substantially as and for the purpose hereinbefore set forth. 80

4. Apparatus for developing photographic roll films in daylight comprising a cylindrical container having an opening in its side, a concentric partition within the container secured to the side thereof adjacent to 85 said opening a reel spindle within the container and an opaque apron adapted to pass through the aforesaid opening and between the partition and the side of the container and to be wound on the aforesaid reel spindle 90 substantially as hereinbefore set forth.

5. Apparatus for developing photographic roll films in daylight comprising a cylindrical container having an opening in its side, a concentric partition within the container secured to the side thereof adjacent to 95 said opening, a reel spindle within the container, an opaque apron adapted to pass through the aforesaid opening and between the partition and the side of the container, 100 and to be wound on the aforesaid reel spindle, a door hinged to the side of the container and having an opening and a spool box adapted to be secured to said door coincidently with the opening therein, substantially 105 as and for the purpose hereinbefore set forth.

6. Apparatus for developing photographic roll films in daylight, comprising a cylindrical casing having an opening in the side 110 thereof, a reel spindle in the container having a wire loop and hooks, an opaque apron adapted to be passed through the aforesaid opening and having hooks for engaging with the hooks on the reel spindle, a door hinged 115 to the container and having an opening, a spool box secured to the door coincidently with the opening therein, and pivots in the spool box for a film spool, substantially as and for the purpose hereinbefore set forth. 120

7. Apparatus for developing photographic roll films in daylight, comprising a cylindrical casing having an opening in the side thereof, a reel spindle in the container having a spring clip and hooks, an opaque apron 125 adapted to be passed through the aforesaid opening and having hooks for engaging the hooks on the reel spindle, milled heads on said reel spindle, one of said heads having a polygonal portion, a brake spring pressing 130

thereon, a door hinged to the container and having an opening, a spool box secured to the door coincidently with the opening therein and pivots in the spool box for a film spool, substantially as and for the purpose hereinbefore set forth.

In testimony whereof I have signed my

name to this specification in the presence of two subscribing witnesses.

JAMES WYNDHAM MEEK.
